UNITED STATES PATENT OFFICE.

EDWIN BIRD WILSON, OF FOREST HILLS, NEW YORK.

DESIGN FOR A FIREPLACE.

Application filed March 8, 1923. Serial No. 5,403. Term of patent 14 years.

To all whom it may concern:

Be it known that I, EDWIN BIRD WILSON, a citizen of the United States, residing in Forest Hills, Queens County, and the State of New York, have invented a new, original, and ornamental Design for Fireplace, of which the following is the specification, reference being had to the accompanying drawing, forming part thereof.

In the drawings Fig. 1 is a front view and Fig. 2 is a side view of a fire place showing my new design.

I claim:

The ornamental design for a fireplace as shown.

EDWIN BIRD WILSON.
